UNITED STATES PATENT OFFICE.

HENRY W. MAURER, OF ROCHESTER, NEW YORK, ASSIGNOR TO HOHMAN & MAURER MANUFACTURING COMPANY, OF ROCHESTER, NEW YORK, A CORPORATION OF NEW YORK.

DESIGN FOR A CASING FOR TEMPERATURE AND PRESSURE GAGES.

No. 38,957.

Specification for Design.

Patented Dec. 17, 1907.

Application filed May 31, 1907. Serial No. 376,744. Term of patent 14 years.

To all whom it may concern:

Be it known that I, HENRY W. MAURER, a citizen of the United States, residing at Rochester, in the county of Monroe and State of New York, have invented a new, original, and ornamental Design for a Casing for Temperature and Pressure Gages, of which the following is a specification, reference being had to the accompanying drawing, forming a part thereof.

Figures 1 and 2 are respectively a perspective view and a side view of a gage embodying my new design.

I claim

The ornamental design for a casing for temperature and pressure gages as shown.

HENRY W. MAURER.
